PAIR OF STANCHIONS FOR A WIND DEFLECTOR FOR AUTOMOTIVE VEHICLES

Frederick A. Helm, 9818 Grinnell, Detroit, Mich. 48213

Filed Dec. 10, 1973, Ser. No. 423,260

Term of patent 14 years

Int. Cl. D12—16

U.S. Cl. D12—155

FIG. 1 is a front elevational view of a pair of stanchions for a wind deflector for automotive vehicles showing my new design, it being understood that the broken lines are for illustrative purposes only.

FIG. 2 is a side elevational view taken along the line 2—2 in FIG. 1.

FIG. 3 is a sectional view taken along the line 3—3 in FIG. 1.

FIG. 4 is a sectional view taken along the line 4—4 in FIG. 1.

FIG. 5 is a perspective view taken in the direction of the arrow 5 in FIG. 1.

FIG. 6 is a side elevational view taken along the line 6—6 in FIG. 1.

What I claim is:

The ornamental design of a pair of stanchions for a wind deflector for automotive vehicles, as shown.
